UNITED STATES PATENT OFFICE.

WALTER WRIGHT, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,270,478.

Specification of Letters Patent. Patented June 25, 1918.

Application filed December 24, 1910. Serial No. 599,183.

To all whom it may concern:

Be it known that I, WALTER WRIGHT, a citizen of the United States, residing in New York, in the county of New York and State 5 of New York, have invented certain new and useful Improvements in Combined Type-Writing and Computing Machines, of which the following is a specification.

This invention relates to combined type-writing and computing machines, and particularly to that class in which writing alone is done at one portion of the line, and both writing and computing at another portion of the line of writing.

10 15 In my former applications, I have illustrated a gang of computing wheels of extraordinary length, so that there was one computing wheel for every letter-feeding movement of the carriage. This permitted 20 the placing of the columns at any desired portions of the work sheet, and the computing of all the numbers as they were written.

The object of the present invention is to improve the machine, especially with a view 25 to adapting it for paper carriages of extraordinary widths, such as accommodate paper twenty inches or more in width for instance, in which machines it would not be desirable to provide a computing wheel for every 30 letter-feeding movement of the carriage, especially since, in such machines, it is generally desired to add only at a few points along the line of writing.

To accomplish this object, I provide a 35 gang of computing wheels of substantial length, but not so long as the length of run of the carriage, and preferably equal in number to only a small fraction of the number of letter-feeding movements of the carriage, but still having the computing wheels 40 sufficiently numerous to accommodate separate footings of each of several columns of figures, each column running into the millions, and to permit such columns to be placed at different positions along the computing gang or head.

I also provide a master wheel for turning the computing wheels, and arrange for relative traveling movement between the master 50 wheel and the gang of computing wheels; in the present instance the master wheel be-

ing adapted to travel. I arrange to have the typewriter carriage pick up the master wheel at any desired point along the run of the typewriter carriage; and I further preferably arrange to cause the typewriter carriage to drop the master wheel after the latter has traversed the entire gang of computing wheels, thus to permit the typewriter carriage to continue to the end of the line of writing. I also arrange for the typewriter carriage, when returning, to pick up the master wheel and to return the latter to its initial position; and preferably, I provide means to enable the typewriter carriage to drop the master wheel again, so that the typewriter carriage can complete its return to begin a new line of writing. Other features and advantages will hereinafter appear; and certain features of the invention 70 may be used in other connections.

In the accompanying drawings,

Figure 1 is a part sectional side elevation of a typewriting and computing machine embodying the present improvements.

Fig. 2 is a part sectional rear elevation of the machine, illustrating the manner of connecting the computing carriage to the typewriter carriage, and also showing in dotted lines the disconnection of said carriages.

Fig. 3 is a part sectional front elevation of the right hand end of the machine.

Fig. 4 is a rear elevation to show the manner of disconnecting the computing carriage from the typewriter carriage.

Fig. 5 is a perspective rear view of the computing carriage and the means for connecting it to the typewriter carriage.

In the Underwood typewriting machine, 90 numeral keys 1 and alphabet keys 2 operate through levers 3 and 4, to swing type bars 5 upwardly to strike against the front of a platen 6 upon a carriage 7, which is driven by a spring barrel 8 and is controlled through said keys by escapement mechanism, 95 including a rack 9 on the carriage, and also including a pinion 10 meshing with said rack and connected to an escapement pinion 11. Key-controlled dogs (not shown) co-operate with said wheel 11 to feed the carriage.

The tabulator in said Underwood machine

comprises keys 12 mounted on levers 13, the rear ends of which thrust up rods 14, having at their upper ends stops 15 to be projected up into the path of an adjustable column 5 stop 16 mounted on a rack 17 supported on the carriage 7; the rack being toothed on its top and bottom faces, and the column stop being of forked construction to embrace the rack bar. As each tabulating rod 14 rises, it 10 swings a universal bar 18 about a pivot 19, and pulls down a link 20 which is connected to a lever 21, the latter pivoted at 22 and carrying on its forward end a roll 23 to lift the carriage feeding rack 9 about its hinge 15 24, so that the carriage may run freely independently of the letter-feeding mechanism until arrested by the coöperation of the column stop 16 and the selected counter-stop 15.

As the numeral keys 1 are operated, a vertical drive shaft 25 (Fig. 3) of the computing mechanism is rotated through varying distances, depending upon the key depressed. This shaft carries a pinion 26 in mesh with a pinion 27, which is fixed upon the end of 25 a shaft 28, to which is splined a master wheel 29, having opposite teeth 30 to engage internal teeth 31 formed on a series of computing wheels 32, said wheels mounted in a casing 33 and meshing with gears 34 formed 30 on number bearing wheels 35.

Said master wheel 29 is caused to travel step-by-step so that it may be presented to the computing wheels in succession, beginning with the left hand wheel at Fig. 3, that is, the wheel of highest denomination. For this purpose, the master wheel is swiveled or joined at 36 to a hollow arbor 37, which is fixed rigidly upon a standard 38 forming part of a computing carriage forward of the typewriter carriage; said standard erected upon a tube 39, which slides upon a rail 40, and also having a bearing 41 to slide upon a parallel rail 42; said rails extending from a block 43 secured upon a bracket 44 which is attached to rods 45, 46, usually forming part of the typewriter framework. The opposite end of the tube or sleeve 39 is secured to a head 47 also sliding upon the rail 42 and carrying an index 45 48 to indicate the number wheels 35.

Upon this computing carriage is fixed, by its ends, a rack 49, which forms part of the means for connecting said carriage 38, 39 to the typewriter carriage 7. This rack 49 is 55 driven by a gear 50 fixed upon the forward end of a shaft 51, the rear end of said shaft carrying a gear 52, and the latter being connected by a gear 53 to a rack 54 formed on a sliding bar or carriage 55; the latter 60 having means for attachment to the paper carriage 7, so as to move in letter feeding direction therewith; and the rack 49 moving in the opposite direction, together with the master wheel 29, so that numbers of higher

denominations are first written and computed, then numbers of lower denominations. The bar 55 runs upon grooved guiding rolls 56 pivoted on the framework back of the typewriter carriage; other grooved rolls 57 being provided to engage the top 70 of the bar; whereby the latter is prevented from displacement, laterally or vertically.

Pivoted at 58 to the rack-bar 55 is the arm 59 of a hook 60, the latter having a catch or lug 61 for engagement with the column stop 62 at a point forward of the counter-stops 15. At Fig. 2, the hook 60 is shown in full lines as held up by a spring finger 63 (bearing in a notch 64 in the bar 55), and in engagement with said column stop 62, so that 80 the latter may pull the hook to the right at Fig. 2, or in letter-feeding direction when the carriage is fed by the operation of the keys 1 and 2, or any of the decimal tabulator keys 12. The column stop, or other carrier 85 upon the carriage 7, pulls the hook 60 and the rack 55 to the right, rotating gear 53 and effecting a reverse rotation of the gears 52 and 50, thereby driving the computing carriage rack 49 in the opposite direction. 90 This movement continues until a releaser 65, pivoted at 66 upon the bar 55, encounters a stop or abutment 67 fixed upon the framework. Continued movement of the carriage 7 and bar 55 causes said releaser 65 to turn 95 about its pivot 66 to the dotted line position seen at Fig. 2, thereby depressing the hook 60 to disengage the catch or tooth 61 from the carrier or lug 62, and permitting the carriage 7 to continue in letter feeding direction, so that the line of writing may be completed.

As soon as the tooth 61 escapes from the column-stop or lug 62, the spring 63, which has been put under tension by the releaser 65, reacts and lifts the hook 60, turning the releaser 65 back to normal position against stop 65* and incidentally thrusting back the bar 55 to permit the return movement of the releaser about its pivot 66. The hook 60 110 is supported against displacement by a headed screw 68 threaded into the bar 55 and passing through a slot 69 in the hook.

It will be understood that in traveling from the full line to the dotted line position at Fig. 2, the hook 60 has moved the master wheel 29 past all of the computing wheels at Fig. 3, stopping at each wheel, and that the master wheel has turned the successive wheels to an extent determined by the keys 120 1 as aforesaid.

When the carriage 7 is run back to begin a new line of writing, the column-stop or lug 62 engages the tooth or lug 61 on the opposite side thereof (the right hand side at Fig. 2) and thrusts the hook toward the left at Fig. 2, that is, in the direction in which the paper carriage 7 is returned. This

drives back the rack bar 55 and turns the gears 53, 52, 50, and moves the computing rack 49 toward the right at Fig. 5 to begin a new computation. This movement continues until an inclined edge 70 upon the hook strikes an interceptor or roll 71, which cams down the hook to release it from the column stop or member 62; whereupon the carriage 7 may be driven still farther toward the left at Fig. 2 until it is in position to begin a new line of writing.

Upon writing the new line, the typewriter carriage will travel independently of the computing carriage until said column stop 62 strikes the upper portion 70* of the inclined edge of the hook 60, thereby forcing the hook down until the spring 63 snaps said hook up, with a notch 72 therein fitting over the bottom edge of the column stop 62. Said stop may be so placed that upon depressing any tabular key 12, the paper carriage and the computing carriage will be brought to the desired decimal position for beginning writing the numbers to be computed. The numbers will then be automatically computed while they are being typewritten.

The work for which this machine is designed is that of making out railway reports which vary greatly in character, both in widths of columns to be computed and in the position of said columns with reference to the descriptive or narrative matter to be written in connection with them, because said descriptive matter sometimes comes at the right of several computed columns, and sometimes at the left of several such columns. The dial or number bearing wheels 35 are herein shown as covering a range of upward of forty letter-spaces of the typewriter carriage, thus permitting the separate footing of four or more adjacent columns of figures each running to the millions. Further, owing to the fact that the dial wheels 35 are connected in a continuous carry-over train, said columns may begin and end at any points within the range of said dial wheels, and adjacent columns may vary in width to any extent so long as they do not overlap. As set forth earlier in this specification, said columns can be located at any point along the travel of the typewriter carriage, and said point is determined by the stop or lug 16.

The only limitation therefore on the number, position and character of columns which this machine will compute is that the printed digits in the columns shall all completely lie within the range of the dial wheels 35, and that said columns shall not overlap onto each other.

It should be explained that when the hook or catch 60 is being depressed by the stationary roll 71, the computing carriage 38

strikes a pin 73, Fig. 3, adjustably secured by a screw 74 in a plunger or buffer 75, and presses said plunger toward the left at Fig. 3, until the disengagement of the catch 60 from the carrier or lug 62 occurs. Thereupon a spring 76, coiled about the stem 77 of said plunger, projects the latter to normal position, and forces the carriage 38 to the right at Fig. 3, and the bar 55 to the right at Fig. 2 sufficiently to enable the hook or catch 60 to rise to normal position; the paper carriage 7 in the meantime completing its return to begin a new line of writing. The pressure of the spring 76 may be regulated by a screw 78. This spring serves to move the carriage 38 until the latter is arrested in initial or normal position by a snap-tooth 79 held upon a spring 80 secured to the framework; said tooth being beveled and engaging a beveled notch 81 in the end of the rack 49. When the carriage is in this position, the index pointer 48 may stand just to the left of the computing wheels, as seen at Fig. 3; and upon the paper carriage being released by the decimal key 12, the adjustable column stop or lug 16 on the carriage will engage the tooth 61 on the hook 60 and be caught in the notch 72, so that when the paper carriage 7 is arrested by the projected decimal or other stop 15, the computing carriage is also arrested in position to compute the number written in the proper column or place on the work sheet.

Variations may be resorted to within the scope of the invention, and portions of the improvements may be used without others, as for instance, the releaser 65 may be used whether or not the hook 60 is returned by the carriage when the latter is run back to begin a new line.

The tens-carrying mechanism, as set forth in certain of my former applications, may comprise a special tooth 82 on each computing wheel, a five-toothed pinion 83 intermittently operable by said special tooth, a pinion 84 meshing with the gear 32 of the next computing wheel and half the diameter thereof, and a five-lobed wheel 85 rigid with said pinions 83 and 84. When this three-part member is turned by the tooth 82, one of the lobes of said five-lobed wheel is brought into engagement with a constantly revolving soft rubber roll 86, which extends the length of the gang of computing wheels; said roll serving to assist the three-part member to complete the tens-carrying operation; a detent 87 seating between the lobes on the member 85 to complete the final portion of their movement, to hold them against jarring. This rubber roll 86 is on a shaft 88 on which is a pinion 89 meshing with a pinion 90 forming a part of a train of gearing to a constantly revolving motor (not

shown). As set forth in said applications, said motor rotates the master wheel through distances controlled by the keys, but the mechanism which accomplishes this result is omitted for the sake of clearness.

5 Having thus described my invention, I claim:

1. In a combined typewriting and computing machine, the combination with a typewriter carriage carrying a projection, and a computing carriage having a hook to engage said projection, so that said computing carriage is controlled by said typewriter carriage in the computing zone; of means 10 for disconnecting and re-connecting said carriages during the travel of the typewriter carriage in opposite directions, including means for automatically depressing and raising said hook.
2. In a combined typewriting and computing machine, the combination with a typewriter carriage, of a computing carriage, means connecting said carriages including a rack carried by said computing carriage, a second rack, gears connecting said first and second racks, a hook carried by said second rack, and means carried by said typewriter carriage for engaging said hook, whereby said typewriter carriage may 15 control the movement of said computing carriage.
3. In a combined typewriting and computing machine, the combination with a typewriter carriage, of a computing carriage adapted to be controlled by said typewriter carriage, means connecting said carriages comprising a projection on said typewriter carriage, a hook engageable by said projection, a rack connected to said hook, a 20 rack carried by said computing carriage, and a shaft including gearing connecting said racks, said shaft extending from the front to the back of the machine.
4. In a typewriting and computing machine, the combination with a typewriter carriage having a lug, of a computing carriage having a hook, means dependent upon the letter space movement of the typewriter carriage for disengaging said hook from 25 said lug, means for restoring the hook to position to be engaged and driven by the lug during the return of the carriage to begin a new line, means dependent upon the return movement of the carriage for disengaging 30 the hook and lug, and means for restoring the hook to position to be reengaged by the lug as the carriage moves in letter-feeding direction.
5. In a typewriting and computing machine, the combination with a typewriter carriage having a lug, of a computing carriage, a hook connected to said computing carriage and engageable by said lug to be 35 picked up and carried along thereby to cause the computing carriage to move step by step at the feeding movement of the typewriter carriage, an abutment, and a pivoted releaser connected to travel with the hook and mounted to be intercepted by said abutment and caused thereby to disengage 40 said hook from said lug.
6. In a typewriting and computing machine, the combination with a typewriter carriage having a lug, of a computing carriage, a hook connected to said computing carriage and engageable by said lug to be picked up and carried along thereby to cause the computing carriage to move step by step at the feeding movement of the typewriter carriage, an abutment, and a pivoted releaser connected to travel with the hook and mounted to be intercepted by said abutment and caused thereby to disengage 45 said hook from said lug; means being provided to elevate or restore said hook and releaser to normal positions.
7. In a typewriting and computing machine, the combination with a typewriter carriage having a lug, of a computing carriage, a traveling bar connected to said computing carriage, a hook or catch on said bar and engageable by said lug to be picked up and carried along thereby to cause the bar to move step-by-step at the letter-feeding movement of the typewriter carriage, an abutment, and a releaser pivoted on said bar to be intercepted by said abutment and caused thereby to withdraw said catch from 50 said lug.
8. In a typewriting and computing machine, the combination with a typewriter carriage having a lug, of a computing carriage, a traveling bar connected to said computing carriage, a hook or catch on said bar and engageable by said lug to be picked up and carried along thereby to cause the bar to move step-by-step at the letter-feeding movement of the typewriter carriage, an abutment, and a releaser pivoted on said bar to be intercepted by said abutment and caused thereby to withdraw said catch from 55 said lug during the letter-feeding movement of the typewriter carriage.
9. The combination with a typewriter carriage and a computing carriage, of a hook or catch to connect them, means dependent upon the return of the typewriter carriage to release said hook and disconnect the carriages, and a spring to advance the computing carriage sufficiently to enable the hook 60 to recover its normal position, so that the hook may again encounter a lug on the typewriter carriage as the latter advances in letter-feeding direction.
10. The combination with a typewriter carriage and a computing carriage, of a hook or catch to connect them, means dependent upon the return of the typewriter 65 carriage to release said hook and disconnect the carriages, and a spring to advance the computing carriage sufficiently to enable the hook to recover its normal position, so that the hook may again encounter a lug on the typewriter carriage as the latter advances in letter-feeding direction.

- carriage to release said hook and disconnect the carriages, a spring to advance the computing carriage sufficiently to enable the hook to recover its normal position, so that the hook may again encounter a lug on the typewriter carriage as the latter advances in letter-feeding direction, and means for adjusting the tension of said spring.
11. The combination with a typewriter carriage and a computing carriage, of a hook or catch to connect them, means dependent upon the return of the typewriter carriage to release said hook and disconnect the carriages, a spring to advance the computing carriage sufficiently to enable the hook to recover its normal position, so that the hook may again encounter a lug on the typewriter carriage as the latter advances in letter-feeding direction, and means for yieldingly holding the computing carriage in the position to which it is moved by said spring.
12. The combination of a typewriter carriage, a rack connected thereto, a computing carriage also having a rack, and a connecting train including gears constantly meshing with said racks, and also including an idle gear to cause the carriages to move in opposite directions.
13. In a combined typewriting and computing machine, the combination with a typewriter carriage, of a computing machine carriage, a lug on said typewriter carriage, a catch for engaging said lug to move said computing machine carriage in both directions, means for moving said catch out of intercepting position when the typewriter carriage is returned to begin a new line, and means for moving said catch so that it will lie in intercepting position during the travel of the typewriter carriage in letter-feeding direction.
14. In a combined typewriting and computing machine, the combination with a typewriter carriage and a lug on said carriage, of a computing machine carriage, a catch for intercepting said lug to move bodily therewith to cause said computing machine carriage to travel therewith in each direction, means for freeing said catch from said lug during the return movement of the typewriter carriage, and means for freeing said catch from the freeing device.
15. In a combined typewriting and computing machine, the combination with a typewriter carriage, of a computing machine carriage, a rack on said typewriter carriage, a lug on said rack, a catch for engaging said lug to move bodily therewith and move said computing machine carriage therewith in each direction, means for moving said catch out of intercepting position when the typewriter carriage is returned to begin a new line, and means for moving said catch so that it will lie in intercepting position during the travel of the typewriter carriage to cause said computing machine carriage to travel therewith in either direction, means for freeing said catch from said lug during the return movement of the typewriter carriage, and means for freeing said catch from the freeing device.
16. In a combined typewriting and computing machine, the combination with a typewriter carriage and a rack on said carriage, of a computing machine carriage, a lug on said rack, a catch for intercepting said lug to move bodily therewith to cause said computing machine carriage to travel therewith in either direction, means for freeing said catch from said lug during the return movement of the typewriter carriage, and means for freeing said catch from the freeing device.
17. In a combined typewriting and computing machine, the combination with a typewriter carriage and a computing machine carriage, of a catch for picking up said typewriter carriage to cause it to move said computing machine carriage, a disconnecting device for positively moving said catch out of the path of said typewriter carriage on the return movement of said typewriter carriage, and a spring for freeing said catch from said disconnecting device.
18. In a combined typewriting and computing machine, the combination with a traveling carriage, of a computing carriage returned by said typewriter carriage and disconnected therefrom on its return, and a centering device adapted to properly position said computing carriage after being disconnected from said typewriter carriage.
19. In a combined typewriting and computing machine, the combination with a typewriter carriage and a computing carriage movable independently of each other, of a releasable connecting means connecting said typewriter carriage and computing carriage whereby said typewriter carriage may return said computing carriage, means for releasing the typewriter carriage from the computing carriage during the return of both carriages, a buffer for absorbing the shock of the computing carriage at the movement of release, and an alining device for said computing carriage acting conjointly with said buffer to properly position the computing carriage in normal position.
20. In a combined typewriting and computing machine, the combination with a typewriter carriage having a lug, of a computing carriage, a hook connected with said computing carriage, and engageable by said lug, to cause the computing carriage to move step by step at the letter-feeding movement of the typewriting carriage, an abutment, and a pivoted releaser connected to travel with said hook, and adapted to be intercepted by said abutment and be moved thereby, to positively cause said hook to be disengaged from said lug.
21. In a combined typewriting and computing machine, the combination with a typewriter carriage and a computing machine carriage, of a catch for intercepting said lug to move bodily therewith to cause said computing machine carriage to travel therewith in either direction, means for freeing said catch from said lug during the return movement of the typewriter carriage, and means for freeing said catch from the freeing device.

- puting machine, the combination with a typewriter carriage having a lug, of a computing carriage, a hook connected to said computing carriage, and engageable by said 5 lug to cause the computing carriage to move step by step at the letter-feeding movement of the typewriter carriage, an abutment, and a pivoted releaser connected to travel with said hook, and adapted to be struck by said 10 abutment and caused thereby to positively disengage said hook from said lug; means being provided to normally hold said lug and releaser in effective positions.
22. In a combined typewriting and computing machine, the combination with a 15 typewriter carriage having a lug, of a computing carriage and a traveling bar connected to said computing carriage, a hook or catch on said bar and engageable by said 20 lug to cause the bar to move step by step at the letter-feeding movement of the typewriter carriage, an abutment, and a releaser pivoted on said bar and adapted to be struck by said abutment and moved thereby, to 25 positively withdraw said catch from said lug.
23. In a combined typewriting and computing machine, the combination with a typewriter carriage having a lug, of a computing carriage, a traveling bar connected to said computing carriage, a hook or catch on said bar and engageable by said lug to cause the bar to move step by step at the letter-feeding movement of the typewriter 30 carriage, an abutment, and a releaser pivoted on said bar and adapted to be moved thereby, to positively withdraw said catch from said lug under the influence of a letter-feeding movement of the typewriter carriage, and means for returning said hook to 35 its effective position when the typewriter carriage has passed, said hook remaining in the path of the lug to be engaged thereby on the return movement of the carriage.
- 40 24. In a combined typewriting and computing machine, the combination with a typewriter carriage having a lug, of a computing carriage including one element of a computing mechanism, a master wheel forming an element of said computing mechanism, a gang of computing wheels adapted to foot separately several separate columns, a traveling bar connected to said computing carriage, a hook or catch on said bar engageable by said lug to cause the bar to move 45 step by step at the letter-feeding movement of the typewriter carriage, an abutment, and a releaser pivoted on said bar to be intercepted by said abutment and caused thereby to positively withdraw said catch from 50 said lug.
- 55 25. In a combined typewriting and computing machine, the combination with a traveling carriage and a stop on the carriage, of a computing machine carriage, a 60 catch adapted to be moved bodily along by said stop for positively causing said computing machine carriage to feed step-by-step with said typewriter carriage in each direction, means for positively freeing said 65 catch from said typewriter carriage by movement of the carriage during the return movement of said carriage, and means for moving said catch into position to be intercepted by said typewriter carriage during 70 the next movement of said carriage in letter-feeding direction.
26. In a combined typewriting and computing machine, the combination with a frame, of a typewriter carriage supported thereon, a computing mechanism, connections between said typewriter carriage and said computing mechanism including a lug carried by said carriage, a shaft supported on said frame, a tube slidable on said shaft, 80 a plate carrying said tube at one end and a rack at the other, said tube supporting a part of the computing mechanism and said rack having geared connection with a hook adapted to be engaged by said lug whereby 85 motion of the typewriter carriage is transmitted to the computing mechanism.
27. In a combined typewriting and computing machine, a typewriter carriage at the rear of the machine, a computing carriage 90 at the front of the machine, means for moving said computing carriage in the opposite direction from said typewriter carriage, said means including a train of three gears, racks carried by the respective carriages and meshing with two of said gears, said third gear meshing with one of said first-mentioned gears and a rack.
28. In a combined typewriting and computing machine, the combination with a typewriter carriage and a computing carriage, of a hook for connecting them together, a fixed lug for automatically releasing said hook, a bar connected to said hook, and an intermediate member pivoted on said 100 bar overlying said hook and adapted to strike said lug to swing said hook to ineffective position.
29. In a combined typewriting and computing machine, the combination with a typewriter carriage and a computing carriage, of a hook for connecting them together, a fixed lug for automatically releasing said hook, a bar connected to said hook, an intermediate member pivoted on said bar 110 overlying said hook and adapted to strike said lug to swing said hook to ineffective position, means for normally holding said hook in a position to reunite said carriages, and connections whereby said hook is effective in both directions of travel of said 115 carriages.
30. In a combined typewriting and computing machine, the combination with a typewriter carriage and a totalizer comprising 120

- ing dial wheels, of a computing carriage connectible to said typewriter carriage, connecting means for picking up and positively carrying said computing carriage along in each direction, a pivoted disconnector traveling with said connecting means, and means coöperating with said disconnector adapted to release said carriages from each other at a predetermined position.
5. 31. In a combined typewriting and computing machine, the combination with a typewriter carriage and a computing carriage, of a hook connecting them together, a fixed lug for automatically releasing said hook, and an intermediate member pivoted to travel with said hook and adapted to strike said lug and to be swung thereby from a position overlying said hook to carry said hook to ineffective position.
10. 32. In a computing machine, the combination with a typewriter having a carriage, a computing mechanism comprising a totalizer adapted to compute and foot separately each of several columns in the travel of said typewriter carriage, carry-over devices for 20 said totalizer, a computing carriage for said totalizer, and means whereby said computing carriage is positively carried by said typewriter carriage in both directions during a limited part of the travel of said typewriter carriage, and is positively disconnected by the travel of said typewriter carriage in each direction of travel thereof.
15. 25. 30.

WALTER WRIGHT.
